UNITED STATES PATENT OFFICE.

JOSEPH J. KELLY, OF DETROIT, MICHIGAN.

BASE-BALL-GAME APPARATUS.

1,128,457.

Specification of Letters Patent. Patented Feb. 16, 1915.

Application filed April 27, 1914. Serial No. 834,758.

To all whom it may concern:

Be it known that I, JOSEPH J. KELLY, a citizen of the United States, residing at Detroit, in the county of Wayne and State 5 of Michigan, have invented certain new and useful Improvements in Base-Ball-Game Apparatus, of which the following is a specification, reference being had to the accompanying drawings.

10 This invention relates to new and useful improvements in amusement devices and more particularly to an amusement device simulating a game of base ball, the main object of the invention being the provision of 15 a base ball game so designed and constructed, whereby the actual game of base ball may be so nearly simulated as to produce the same amount of enthusiasm and delight experienced in witnessing a real game.

20 Another object of the present invention is the provision of an amusement device of the above character which will possess advantages in points of efficiency and durability, is inexpensive to manufacture and, at 25 the same time, is simple in construction and operation.

With the above and other objects in view, the invention consists in the novel features 30 of construction, combination and arrangement of parts as will be hereinafter referred to and more particularly pointed out in the specification and claims.

In the accompanying drawing forming a part of this application, Figure 1 is a top 35 plan view illustrating a game board constructed in accordance with my invention; Fig. 2 is a transverse sectional view illustrating the relative sizes of the balls used in my improved game; and Fig. 3 is a detail 40 perspective view of a modified form of ball member used in connection with my improved game.

In the construction of my improved amusement device, the base or playing field 45 is constructed of card board stamped out to imitate a base ball diamond and park, the base board preferably being formed somewhat oval in design and is provided at its outer edge with an up-turned flange 2. The

central portion of the base board is provided 50 with a groove 3, which is formed of a design substantially in the shape of a diamond and the base corners which are known as first, second and third base and the home plate, are generally indicated by the numerals 55 4, 5, 6 and 7. Communicating grooves 8 and 8' are adapted to connect at the inner ends with the portion indicated as first base and are adapted to extend outwardly upon the opposite side of that portion of the 60 groove which connects first and second base and mounted for movement within said grooves, is a movable element 9 which will be known in the game as the first base guard. Communicating with that portion 65 of the groove 3 which is designated as second base, are the oppositely extending grooves 10 and 11, the groove 10 having mounted therein a movable element 12 which will be known as a second base guard and 70 mounted in the groove 11, is a movable element 13 which will be known as the short stop. Extending outwardly from that portion of the diamond which is designated as 75 third base, are the grooves 14 and 14' and mounted for movement therein, is the element 15. Arranged adjacent that portion 80 of the diamond which connects the third base and home plate, is a slightly curved groove 16, in which the movable element 17 is mounted and which in the game is 85 designated as the catcher, the inner end of this groove terminating directly in the rear of the home plate portion as indicated in Fig.

1. Mounted for movement within the groove 85 3, is a movable member 18 which is designated as the runner and which is adapted to be moved around in the groove 3.

The ball which is indicated by the numeral 19 is mounted upon the playing field 90 and is to be of a sufficient size so that the same will not become lodged within any of the various grooves formed in the base. Formed in the base 1, at one end of the field, are the transverse grooves 20 and mounted 95 therein, are the movable elements 21 which are designated as the fielders. Formed within the diamond, is a longitudinal groove 22

which communicates at one end with a substantially circular portion 23 formed in the center of the diamond and terminates at the other end at that portion of the diamond 5 which is known as the home plate. As stated before, the ball which is indicated by the numeral 19 is formed of a size whereby the same may readily roll upon the playing field and not become lodged within any of 10 the grooves and in playing the game the person operating the same will be the batter.

The object of the game is to operate the board by tilting the same so that the runner 15 18 will be moved around the diamond in the groove and the ball moved outwardly over the playing field in such a manner that the same will not contact with any of the players, and should the ball in its movement 20 come in contact with any one of the players, the runner 18 which is being moved about the groove will be out. Thus if the ball 19 is passed beyond the first base portion and is moving toward the second base portion 25 and the ball 19 contacts with one of the players, the batter will be out. If, on the other hand, the ball 19 moves about the playing field without contacting with any of the players, while the runner 18 is being moved 30 about the grooves forming the diamond, a run will be counted. It will be noted that when the board is tilted to move the runner 18 along the groove, the ball 19 will roll outwardly upon the field and the score of the 35 operator is required in order to prevent the ball 19 from contacting with any of the players. If the runner has reached the base portion before the ball contacts with any of the players, a hit will be counted and if the 40 ball reaches a second base portion before the ball has contacted any of the players, a two base hit will be counted and so on.

It will be apparent from the accompanying drawings that the grooves which communicate with the main groove 3 are provided at their inner ends with the offset portion 8' and it will be apparent that the spherical members which are arranged within the grooves communicating with the main 45 groove will be prevented from entering the main groove 3 by means of the offset portions, which extend inwardly into said grooves. Thus it will be apparent that as the runner 18 is disposed around the groove 3, the 50 spherical members representing the baseman will rotate within their respective grooves and when at the inner ends thereof will project beyond the side walls sufficient to tag the runner should they both meet in 55 one of the corners. The baseman will tag the runner unless prevented by the skill of the operator. Extending outwardly from each side of the central depression 23, are

the grooves 23' which are adapted to form a race-way for a spherical element designating 65 the pitcher.

In Fig. 3, I have illustrated a slightly modified form of member to be used in place of the ball 19. From this it will be apparent that upon tilting the board, the rectangular 70 member 24 will pass over the surface and should one of the numerals thereon be face up when the same stops, the runner is entitled to the number of bases indicated thereby and it will be noticed that the numerals 75 placed upon this rectangular member are from one to four inclusive, so that either a single base hit or a home run may be registered.

From the above description taken in connection with the accompanying drawing, it will be readily apparent that I have provided a simple game of the class described which is closely simulated to the regular game of ball. 80

In view of the inexpensive material of which the device is constructed it will be understood that the same may be manufactured and placed upon the market at a comparatively low cost. 85

While I have shown and described the preferred form of my invention, it will be obvious that various changes in the details of construction and in the proportions may be resorted to for successfully carrying my 95 invention into practice, without sacrificing any of the novel features or departing from the scope of the invention, as defined by the appended claims. 90

Having thus described this invention, 100 what I claim is:—

1. A device of the class described including a base board having a plurality of grooves formed therein, movable elements mounted within said grooves, a ball member, 105 said ball member having a diameter greater than the width of the grooves and adapted to be moved over the base and prevented from lodging within any of the grooves, as and for the purpose set forth. 110

2. A device of the class described having a groove formed therein, of substantially diamond-shaped design, obliquely disposed grooves connected with the diamond shaped 115 grooves at various points thereof, movable elements arranged within said second grooves, a movable element mounted within the diamond-shaped groove, and a ball member, said ball member having a diameter greater than the width of the grooves, as and 120 for the purpose set forth.

3. A device of the class described including a base board having a groove formed therein of substantially diamond-shaped design, obliquely disposed grooves connected 125 with the diamond-shaped groove at various

points thereof, movable elements arranged within the second grooves, said board having transverse grooves formed therein and arranged in spaced relation with the diamond-shaped groove, a movable element mounted within the diamond-shaped groove, movable elements arranged within the oblique grooves, and a ball member having a diameter greater than the width of the grooves

and adapted to be moved over the base and prevented from contacting with any of the movable elements.

In testimony whereof I hereunto affix my signature in the presence of two witnesses.

JOSEPH J. KELLY.
